GILLESPIE SWEENEY, OF NEW YORK, N. Y.

Letters Patent No. 96,848, dated November 16, 1869.

IMPROVEMENT IN COMBINED UMBRELLA, CANE, AND SEAT.

The Schedule referred to in these Letters Patent and making part of the same.

To all whom it may concern:

Be it known that I, GILLESPIE SWEENEY, of the city, county, and State of New York, have invented a new and improved Combined Cane, Umbrella, and Seat; and I do hereby declare that the following is a full, clear, and exact description thereof, which will enable others skilled in the art to make and use the same, reference being had to the accompanying drawings, forming part of this specification.

This invention relates to an improved cane, seat, and umbrella, combined together in one article, in an arrangement capable of adjustment for use in the capacity of either one of the said articles; and consists of a sheath answering for the cane, divided into three parts, and enclosing in one part the umbrella, from the point below the lower ends of the ribs, when folded. The stalk is enlarged at this point, and provided with ribs, braces, and a web of canvas, stitched across the ends of the ribs, which spread out similarly, in some respects, to the umbrella, and form a seat, when the top is placed on the ground.

This latter part is enclosed within the part of the sheath forming the handle, which is divided, longitudinally, from the top down, and hinged to the aforesaid enlargement of the stalk. These two parts fasten together by a spring-catch.

Figure 1 is a sectional elevation;

Figure 2 is an elevation of the umbrella, with a part of the sheath detached; and

Figure 3 is an elevation, showing the position when adjusted for a seat.

Similar letters of reference indicate corresponding parts.

A is the lower part of the sheath, enclosing the umbrella above the handle, and consists of a hollow, tapered tube.

B is the other part, enclosing the part of the um-

rella answering to the handle, but which, according to my improvement, constitutes a seat.

This part B is in the form of a hollow handle, and is divided, longitudinally, into two parts, and each is hinged, at C, to a boss, D, on the stalk of the umbrella.

To this boss are jointed strong arms E, in a manner similar to the joining of the arms or ribs of an umbrella, and so as to fold around the stalk and expand in the same way.

F are braces, connected to the arms and to the stalk a short distance from the joint of the said arms.

G is a web, of canvas or other suitable substance, connected to the ends of the arms, so that when they are spread, the canvas will stretch out, as represented in fig. 3, so that the whole forms an excellent seat for field-use.

H is a spring-catch for holding the two parts B of the handle together when the seat is folded up.

The part A of the seat may have any suitable means of connection to the boss C, for holding them together while using as a cane or seat.

When the umbrella is to be used, the sheath A is to be slipped off.

Having thus described my invention,

I claim as new, and desire to secure by Letters Patent—

1. The combination of a cane, umbrella, and seat, in one article, substantially in the manner described.

2. The arrangement, with the stalk of an umbrella, of the arms E, braces F, and canvas or other web G, all substantially as specified.

The above specification of my invention signed by me, this 28th day of September, 1869.
